BUN SLICING MACHINE

David R. Spilky, Chicago, Ill.

Application April 21, 1949, Serial No. 88,773

1 Claim. (Cl. 146—73)

1
This invention relates to a bun or roll slicing machine.

An object of this invention is to provide a slicing machine for buns or rolls wherein a cut is made partially through the article, the machine including an adjustable guide means whereby different sizes of articles may be sliced.

Another object of this invention is to provide in a slicer of this kind an improved mounting for securing to the motor, so that the slicer housing may be rigidly secured to the motor and will enclose one end of the motor so that bread particles will not enter the motor casing.

A further object of this invention is to provide in a slicing machine an improved gate or guide for the articles including supports for the gate or guide and bushings for the supports which are removable in the housing sections.

With the above and other objects in view, my invention consists in the arrangement, combination and details of construction disclosed in the drawings and specification, and then more particularly pointed out in the appended claim.

In the drawing:

Figure 1 is a plan view of a bun slicing machine constructed according to an embodiment of this invention.

Figure 2 is a sectional view taken on the line 2—2 of Figure 1.

Figure 3 is a fragmentary sectional view taken on the line 3—3 of Figure 1.

Figure 4 is a fragmentary sectional view taken on the line 4—4 of Figure 2.

Figure 5 is a fragmentary sectional view taken on the line 5—5 of Figure 2.

Figure 6 is a fragmentary sectional view taken on the line 6—6 of Figure 2.

Figure 7 is a fragmentary sectional view taken on the line 7—7 of Figure 2.

In the drawing, the numeral 10 designates generally a conventional motor 10 which is mounted on a base 11 having a cushioned foot 12. The motor 10 with the base 11, is adapted to be mounted adjacent one edge of a supporting member 13 which may be a table or the like, the purpose for which will be hereinafter described.

A housing generally designated as 14, is mounted on the forward end of the motor 10 and comprises complementary housing members 15 and 16 which are secured together by means of bolts 17. The housing member 15 comprises a vertically disposed wall 18 having an annular flange 19 which is adapted to engage about the forward end of the motor 10. The wall 18 has extending therethrough, bolts or screws 20 which are

2

threaded into the forward end of the motor 10 for holding the housing 14 firmly to the motor 10. The wall 18 is provided at the outer marginal portion thereof with a right angularly projecting flange 21, and the vertical wall 22 of the outer housing member 16 is formed with a flange 23 confronting the flange 21 and forming therewith a chamber 24 within which a circular cutting blade 25 is adapted to be loosely mounted. The blade 25 is secured to a bushing 26 by fastening means 27 and the bushing 26 is secured to the motor shaft 28 by fastening means 29.

The housing 14 includes a vertically disposed and substantially tangentially arranged guide generally designated as 30, which includes inner and outer semi-elliptical members 31 and 32. The blade 25 projects a substantial distance into the guide 30 so that when buns or rolls are dropped downwardly into the guide 30 these buns or rolls will be split for a substantial distance but leaving a small portion of the bun or roll forming a hinge so that the desired article, such as a frankfurter or hamburger patty may be inserted in the bun or roll.

A vertically disposed and adjustable gate or inner guide 33 is disposed within the guide 30 being of transversely arcuate configuration and flared at the upper and lower ends 34 and 35 respectively. The adjustable guide 33 has secured thereto, adjacent the upper and lower ends thereof, a pair of supporting rods 36 and 37 which slidably engage in the upper and lower bushings or bearings 38 and 39 respectively. Each bearing, as shown in Figure 4, includes a reduced inner bushing 40 engaging in a bore 41 and a set screw 42 is threaded through an enlarged boss 43 and projects through the reduced bushing 40 and is adapted to bear against a supporting rod 36 and 37 so as to firmly secure the supporting rod in horizontally adjustable position and at the same time to hold the bushing against endwise movement. As shown in Figure 2, the upper and lower ends of the guide 30 are flared outwardly, as shown at 44 and 45 respectively, so that the articles may be readily inserted into the guide 30 and so that if desired the housing 14 may be reversed as to reverse the position of the guide 30 with respect to the motor 10.

In the use and operation of this device, the motor 10 and the base 11 are mounted on the table or other plane surface with the guide projecting from the edge of the table or plane surface 13. The adjustable gate or inner guide 33 is adjusted within the guide 30 so as to provide

the desired guiding channel for guiding the bun or roll past the cutting blade 25. As herein disclosed, the gate or adjustable guide 33 is adjusted for use of the long frankfurter rolls. As the articles move downwardly through the guide 30, they will pass the rotating cutting blade 25 and will be split by this blade leaving a small portion of the article uncut so as to form a hinge. Where it is desired to split the round hamburger rolls, the gate or guide 33 is adjusted to the right as viewed in Figures 2 and 3 so that these larger rolls can readily and freely slide downwardly through the guide 30.

I do not mean to confine myself to the exact details of construction herein disclosed but claim all variations falling within the purview of the appended claim.

I claim:

A bun slicing machine comprising a power member, a circular cutter rotatable by said member, a housing enclosing said cutter, an annular flange carried by said housing engaging about one end of said member, a tubular vertical bun guide carried by said housing, said guide having parallel straight side walls equidistantly spaced on opposite sides of said cutter, said side walls being connected by oppositely concaved end walls of identical radius of curvature, one of said end walls being provided with a longitudinally extending slot through which said cutter extends

10
15

to a point adjacent, but spaced from, the other of said end walls, said slotted end wall being provided with apertures above and below the slot, bushings in said slot, upper and lower slide members extending through said bushing and a transversely arcuate movable guide member extending the full length of said guide secured to said slide members, said movable guide member being convexed relative to said slotted end wall and of the same radius of curvature, and provided with a second slot aligned with the slot in said end wall through which said cutter extends, whereby movement of said slide member varies the relative position of said guide and hence the cross sectional area of said tubular guide, and said other end member and said guide coat to center a bun passed through said tubular guide and insure a centered cut by said cutter.

DAVID R. SPILKY.
